PLOW

John Blue, Jr., Laurinburg, N. C.

Application January 11, 1939, Serial No. 250,253

4 Claims. (Cl. 97—110)

This invention relates to a plow having novel means for adjusting the plow standard relative to the beam and holding it in such adjustment. It is a well known fact that various plows require various adjustments as to the plow standard, the adjustment or pitch that the standard occupies, depending upon the soil which is being cultivated. By having an adjustable plow standard, it is possible to vary the depth that the plow point passes into the earth, which in turn will increase or decrease the power necessary to draw the plow along. It is very essential that this adjustment be finely graduated and it is equally important that the adjusting member be such that when a proper adjustment has been made that the same will remain in this position.

It is, therefore, an object of this invention to provide means for adjusting a plow standard relative to the beam which will enable one to fix the standard at any desired angle. The particular adjustment shown in the drawing has a specially designed eccentric lock that makes the adjustment positive and very speedy. The plow hoe or sweep upon the foot of the standard is easily and quickly adjusted to the correct angle for plowing by merely lifting a handle, which disengages a clamp associated with the upper portion of the standard and which encircles the plow beam. This eccentric lock enables one to quickly make a most minute adjustment and eliminates the necessity of using bothersome set screws and levers found in conventional stocks.

It is another object of this invention to provide a special type of flat runner or landslide for a plow of this type, said landside being disposed on the lower end of the plow and being adapted to fit in the bottom of a furrow. The landside is secured to the plow by a bolt, the head of which is disposed in a counter-sunk bore in the bottom of the slide. The depth of this bore is much greater than the depth of the bolt head. By providing a suitable counter-sunk bore, in the lower portion of the runner, it is possible to place the head of the bolt at a substantial distance from the wearing surface, thereby allowing the runner to be almost worn out before the head of the bolt is contacted. This insures that the head of the bolt will not be worn away to thus allow the landside to become detached from the plow.

Some of the objects of the invention having been stated, other objects will appear as the description proceeds when taken in connection with the accompanying drawing, in which—

Figure 1 is a perspective view of a plow embodying my invention;

Figure 2 is an enlarged elevation of the central portion of Figure 1 showing the improved

clamp and adjusting means for the plow standard;

Figure 3 is a sectional view taken along the line 3—3 in Figure 2;

Figure 4 is a sectional plan view taken along the line 4—4 in Figure 1;

Figure 5 is a sectional view taken along the lines 5—5 in Figures 1 and 4;

Figure 6 is an isometric view looking at the top side of my improved landside.

Referring more specifically to the drawing, the numeral 10 denotes a plow beam having a hook 11 which is used to draw the plow from place to place. The left-hand end of beam 10 is curved downwardly and has secured to its lower end, as at 14, suitable horizontal strap iron members 15, there being a strap iron member disposed on each side of the beam. These strap iron members occupy side by side relation to each other and jointly form an attaching member to which a landside 16 is secured. At the point where the landside is secured to the members 15, it will be noted that these members are spread apart from each other, forming a slot 17 therebetween, and this slot is penetrated by a bolt 18. The landside 16 has upwardly extending flanges 16a integral therewith for the purpose of reinforcing the same at the point where the bolt penetrates this member.

By referring to Figures 5 and 6, it is seen that a slot 19 is provided in the landside 16. This slot is countersunk on the bottom side and the head 18a of the bolt 18 is adapted to fit therein. This slot is so constructed that the head of the bolt will be disposed at a considerable distance from the wearing surface 21 of the landside. Therefore, by providing a landside of this type practically all of the same can be worn away before the head 18a of the bolt 18 will be contacted. Heretofore, it has been common practice to provide a counter-sunk hole or slot of such a depth that the head of the bolt would be substantially even with the wearing surface of the bottom side of the landside, resulting in the head of the bolt wearing from the beginning along with the landside. When the old type of landside is used, the head of the bolt will be almost completely worn out before the slide or runner has been worn a corresponding amount.

The front ends of the attaching members 15 are secured to the lower end of standard members 22 as at 23. This standard comprises a pair of spaced bars which extend upwardly and have their upper ends disposed on opposed sides of beam 10. Disposed between the bars 22 and directly beneath the beam 10, is a block 25. This block has an upper convex surface which fits into the concave surface on the lower side of the beam 10. The block 25 is held between members 22 by any suitable means such as a bolt 26 and this bolt has

a spacer sleeve 27 therearound. The upper side of the beam 10 is convex and has the lower concave surface of a block 28 fitting thereagainst. This block has a notch in the upper side thereof which notch is engaged by the periphery of an eccentric head portion 31, said eccentric portion being integral with handle 32 weighted at its free end. The handle and the eccentric portion are pivoted as at 33 between the members 22. When it is desired to release the clamping pressure between the block 28 and the upper side of the beam 10, it is only necessary to rotate the handle 32 to a dotted line position. Due to the eccentricity of the portion 31 relative to the bolt 33, the clamping pressure will be relieved at this time. When the lever or handle 32 is in dotted line position the standard members 22 may be rotated either in a clockwise or counter-clockwise direction relative to the pivot point 23. This 20 rotation will of course vary the angularity of plow point 35 which is disposed on the lower portion of the standard. It will also vary at the same time the pitch of the point relative to the ground which is being plowed.

25 This type of clamp makes it possible to get an adjustment which is very fine and which is very positive. In the conventional mechanisms of this type, it has not been possible to use a simple attachment and get fine adjustments due to the fact that notches were used for holding the plow standard in the position after it was once adjusted. These notches could not be spaced closely enough together. By using my improved clamp type of adjustment, an incremental movement can be made and consequently incremental adjustment will result.

The plow beam 10 has suitable handles 37 secured thereto as at 38. These handles have their intermediate portions supported by a brace 39 which brace has its upper end secured to the handles as at 49 and its lower end secured to the rear portion of the beam as at 41.

In the drawing and specification, there has been set forth a preferred embodiment of the invention, and although specific terms are employed they are used in a generic and descriptive sense only and not for purposes of limitation, the scope of the invention being set forth in the appended claims.

50 I claim:

1. A plow having a beam provided with an arcuate rear portion, a horizontally disposed member having its rear end secured to the rear end of the beam, a plow standard having its lower end pivotally secured to the forward end of the member, the upper end of the plow standard being forked and having the beam disposed in said fork, a convex member loosely secured in said fork and having its convex surface in engagement with the concave edge of the plow beam, the fork also having disposed therein a second member provided with a concave surface in engagement with the convex upper edge of the plow beam, the upper edge of the second member having a notch in its upper edge, a lever having an eccentric portion disposed in said notch, means pivotally and eccentrically mounting the eccentric end of the lever between the upper ends of the forked member, whereby rotation of the lever on its pivot in one direction will press the second member into intimate contact with the upper edge of the plow beam to adjust the posi-

tion of the upper end of the standard with relation to the plow beam.

2. A plow having a beam provided with an arcuate rear portion, a horizontally disposed member having its rear end secured to the rear end of the beam, a plow standard having its lower end pivotally secured to the forward end of the member, the upper end of the plow standard having its lower end pivotally secured to the forward end of the member, the upper end of the plow standard being forked and having the beam disposed in said fork, a second member loosely secured in said fork and having a convex surface in engagement with the concave edge of the plow beam, the fork also having disposed therein a third member provided with a concave surface in engagement with the convex upper edge of the plow beam, the upper edge of the third member having a notch in its upper edge, a lever having an eccentric portion disposed in said notch, means pivotally and eccentrically mounting the eccentric end of the lever between the upper ends of the forked member, whereby rotation of the lever on its pivot in one direction will press the third member into intimate contact with the upper edge of the plow beam to adjust the position of the upper end of the standard with relation to the plow beam, said first member having a landslide secured to the lower surface thereof, said securing means comprising a bolt penetrating the first member, said landslide having an elongated slot therein the walls of which taper inwardly and upwardly towards each other to the upper surface of the landslide, the head of the bolt being disposed in said slot and having the lower end of the head portion disposed a substantial distance from the lower surface of the landslide.

3. A plow having a beam, a standard and a slide, the slide having its rear end secured to the rear end of the beam, the standard having its lower end pivotally secured to the forward end of the slide, the rear portion of the beam being curved on an arc of a circle whose center is the pivot point between the standard and the slide, the standard comprising a pair of members projecting alongside and beyond the upper edge of the beam, a bolt penetrating said members a short distance below the beam, a wedge member having a notch in its lower side in which said bolt is disposed and having a convex upper surface fitting against the lower edge of the beam, a second bolt penetrating said members a substantial distance above the upper edge of the beam, a second wedge member having a concave lower surface resting on the upper edge of the beam and having a notch in its upper edge, a lever having an eccentric portion pivotally mounted on said second bolt and disposed in the notch in the upper edge of the second wedge member, whereby, when the lever is swung on its pivot in one direction the wedge members will grip the upper and lower edges of the beam and hold the upper end of the standard in adjusted position.

4. A landslide for plows having an elongated slot therein for receiving an attaching bolt, the slot having sidewalls which converge upwardly to provide a restricted slot at the upper side of the landslide to thereby confine the head of an attaching bolt at a substantial distance from the lower surface of the landslide.
